UNITED STATES PATENT OFFICE.

ARTHUR B. WRIGHT, OF HINSDALE, ILLINOIS.

RADIATION-REGULATOR.

1,152,585.

Specification of Letters Patent.

Patented Sept. 7, 1915.

Application filed December 14, 1912. Serial No. 736,732.

To all whom it may concern:

Be it known that I, ARTHUR B. WRIGHT, a citizen of the United States, and a resident of the city of Hinsdale, in the county 5 of DuPage and State of Illinois, have invented certain new and useful Improvements in Radiation-Regulators; and I do hereby declare that the following is a full, clear, and exact description of the same, reference 10 being had to the accompanying drawings, and the numerals of reference marked thereon, which form a part of this specification.

The radiators provided for cooling internal combustion engines, and more particularly for automobiles, have heretofore presented the same surface for radiation independently of variation in weather conditions, notwithstanding that the amount of radiating surface required in winter is very 15 small as compared with that required during the summer months in most localities. Attempts are frequently made to reduce the radiator surface in cold weather by securing a sheet of paper over the radiator to 20 reduce the space for the admission of air therethrough. This has not proven satisfactory, inasmuch as it is impossible by such means to properly adjust the radiating surface to the requirements of the engine. It 25 frequently happens also during summer weather that the performance of such an engine is seriously affected on cool days when more or less motor difficulty is occasioned which might be easily avoided if the 30 radiating surface could be quickly and satisfactorily adjusted to the proper requirements of the engine.

The object of this invention is to provide 35 a device adapted for use in connection with a radiator whereby the radiator surface may be increased to its maximum, or adjusted to any required amount less than maximum when desired, and maintain its adjustment under all conditions until again adjusted by 40 the operator.

It is a further object of the invention to afford a construction for regulating the draft of air through radiators to suit the requirements of weather conditions.

50 It is also an object of the invention to afford a construction admirably adapted to permit attachment of a distinguishing sign, character, number or symbol on the front of the radiator.

55 It is an important object of my invention to afford a construction whereby the radia-

tion will be shown upon a suitable scale, thereby indicating to the operator the adjustment.

The invention embraces many novel features and in a preferred form is hereinafter more fully described.

In the drawings: Figure 1 is a front elevation, with parts omitted, of an automobile equipped with a regulating device embodying my invention. Fig. 2 is a fragmentary side elevation thereof, broken away. Fig. 3 is a section taken on line 3—3 of Fig. 2. Fig. 4 is a section taken on line 4—4 of Fig. 3. Fig. 5 is an enlarged, fragmentary detail 70 in front elevation. Fig. 6 is a fragmentary front elevation illustrating the attachment of a monogram, number plate or other sign or device upon the regulating means. Fig. 7 is an enlarged, fragmentary, front elevation of the regulating means. Fig. 8 is a fragmentary section taken on line 8—8 of Fig. 5. Fig. 9 is a fragmentary section taken on line 9—9 of Fig. 6. Fig. 10 is a fragmentary section on line 10—10 of Fig. 6. 75

As shown in the drawings: 1, indicates the radiator, which may be of any preferred or suitable kind, constructed in cellular form or pipes, as preferred, the same communicating at the top and bottom and sides, in 80 the usual reservoir to enable the device to hold a sufficient quantity of water, and being provided with a supporting frame 2 for the radiator, as shown. Said surrounding frame is extended forwardly from 85 the reservoir proper to afford a space between the front thereof and the radiating surfaces for the installation of the regulator, and secured within the frame thus afforded at the top thereof, is a guide 90 cleat 3, and at the bottom a guide cleat 4, shown as metallic angle bars rigidly bolted or otherwise secured to the front plate 5, of said frame. Also rigidly bolted to said front plate at the top and bottom thereof, 95 is a grid 6, constructed of sheet metal or any suitable material, and which may comprise relatively thin bars arranged in parallel relation, as shown, and at a sufficient distance apart to permit a draft of air therethrough 100 sufficient for the maximum requirements for the radiator, though, of course, if desired, any fanciful or ornamental configuration for said grid may be employed consistent with permitting the requisite draft of air there- 105

through.

Mounted to slide between the cleats 3 and

4, is a similar grid 7, adapted for adjustment in one direction to close or partly close the openings through the grid 6, and in the other direction to permit unobstructed flow 5 therethrough. Said grid 7, is of less width than the outer grid 6, and rigidly secured at each side thereof, are outwardly directed threaded bolts 8, which extend through the lateral walls of the radiator, and are provided 10 at the outer end thereof with adjusting nuts 9, whereby said inner grid 7, may be adjusted laterally in either direction to permit full opening through said grids or to restrict the openings therethrough, as required. 15

As shown also, a bolt 10, having a head 11, affording an indicating finger, is inserted through horizontal slots in the outer frame plate 5, of the radiator, and in the 20 bottom bar of the outer grid 6, as shown in Figs. 5 and 8, and is threaded at its inner end into the rear grid 7, and a scale indicated by Y, is marked in any suitable manner upon the bottom frame plate 5, of the 25 radiator adjacent said indicating finger, to permit the operator to know by inspection, the relative adjustment of said grids. Inasmuch as said grids may be made of relatively thin and light material, means are 30 provided for rigidly securing the grids together in their adjusted position at or near their middle, and for this purpose the number plate, the monogram, or any suitable device or designating tablet, is utilized. As 35 shown in the drawings, the monogram 13, is used, and, of course, if a number plate is used for this purpose, the body of the plate may be cut away to afford apertures for the air therethrough around the numbers. In 40 either event, the front grid 6, as shown in Figs. 3 and 10, is provided with transverse webs 14, integral with and connecting some of the bars thereof near the middle of the grid and horizontally slotted, and screws or 45 bolts 15 are inserted through the monogram or tablet and through said slotted apertures in the front grid and threaded into the rear grid, thereby firmly clamping the grids together at their middle. If desired, thumb 50 screws may be used for this purpose, permitting quick manual release without necessitating the use of a tool.

The operation is evident from the foregoing.

55 In warm weather, when maximum radiating efficiency with maximum radiation

is required, the grids are adjusted relatively each other to afford the maximum opening for the circulation of air through the radiator, and the degree of 60 opening is varied to suit climatic conditions. Thus an operator is enabled at all times to adjust the radiation to the requirements of the engine or motor, thereby obviating a serious cause for loss of engine efficiency not generally understood by the operators of such machines. 65

Of course, although I have shown the device installed within the radiator frame, it is to be understood that the same may be attached at the front of the radiator in any suitable manner, and wholly outside the radiator frame, if desired, thus adapting the device for installation on water cooled engines of any and all kinds and description. 70 75

It should be understood that while I have shown a monogram attached to the regulating device, the use thereof is intended as merely illustrative, and that a monogram or a registration number or both may be used 80 for this purpose, as preferred. I have shown but one (and that a preferred) form of my invention, and it is to be understood that I do not purpose limiting myself otherwise than necessitated by the prior art, as numerous details of construction may be varied without departing from the principles of my invention. 85

I claim as my invention:

A register, comprising a frame, a stationary grid vertically disposed in said frame, a pair of transverse parallel angular bars rigidly secured to the top and bottom on the inner side of said frame, an adjustable grid 90 slidably mounted between said bars and co-acting with said stationary grid to control the draft therethrough, a pair of outwardly directed bolt members connected at each side of said adjustable grid and extending loosely through the lateral walls of the frame, 95 and adjusting members movably mounted on said bolt members to shift said adjustable grid laterally in either direction to vary the draft therethrough. 100

In testimony whereof I have hereunto subscribed my name in the presence of two subscribing witnesses. 105

ARTHUR B. WRIGHT.
